UNITED STATES PATENT OFFICE.

SAMUEL H. SHAW, OF NEW YORK, N. Y., ASSIGNOR TO UNIVERSAL SHOCK ELIMINATOR, INC., OF LONG ISLAND CITY, NEW YORK, A CORPORATION OF NEW YORK.

BUMPER.

Original application filed July 13, 1922, Serial No. 574,638. Divided and this application filed August 26, 1926. Serial No. 131,611.

This invention relates to bumpers, so-called, such as are used on motor cars to receive the shock of impact with other cars or obstacles on the road. This invention relates to such articles which are sometimes called impact bars, and more particularly to the type known as spring bar or flat spring bar bumpers, in which the impact shock is absorbed by the resiliency of the bumper as distinguished from the type having a rigid bar with a coil spring or similar attaching device to absorb the shock of impact solely in the attaching means or junction of the device with a rigid part of the vehicle.

More particularly this invention relates to improved features of construction of the resilient or impact flat spring bar having for its objects economy in production, durability, lightening of construction, increase strength, and other features the advantages of which will appear from the more detailed specification. Also a particular feature incident to the practice of my invention is the prevention of slipping of the flat spring bar forming the outer impact member, so as to assure a direct reaction on yielding parts of the bumper by having the impact surface held against up or down slipping on the object with which it contacts.

While the construction embodying my invention realizes several or all of the objects set forth, a particular embodiment herein-after specifically described, includes a resilient front impact bar which on its outer vertical face or impact surface has a plurality of narrow bands or strips slightly offset from the other portion of the impact face surface, and a particular feature of this divisional application is the formation of the surface of such bands or strips or some of them in a manner to cause two engaging spring bumper bars to slip into positive engagement to absorb the impact by the bars, and to avoid one bar sliding above or below the other.

This is accomplished in its preferred form by having narrow borders at or near the top and bottom of the impact face, but each in width forming only a fraction of the total width of the impact surface, and therefore only a fraction of the total outer surface of the spring bar that it is necessary to grind and polish, and as is usual in the

finish of this class of product, to nickel-plate. 55 This provides substantial economy in these various operations mentioned in the manufacture. The bands are preferably finished by polishing and nickelizing, but the intervening surface, slightly offset from the vertical 60 plane of the bands, need not be finished or ground, but meets all the requirements by being left in an unfinished condition and suitably japanned, enameled or treated in 65 similar manner. As this type of bumper is used on the front of automobiles and also on the rear, they are constantly exposed to the elements and also exposed to rough usage by impact and scraping on objects, so that 70 minimizing the amount of surface subjected to a fine polish, my construction has many advantages in durability and retaining its appearance in spite of regular usage, with obvious economy.

As these bumpers extend either forward 75 or to the rear beyond the other parts of the vehicle, for the object of shielding other parts of the vehicle against accidental impact, the overhanging weight of the bumper subjects the attachment to the rigid part of 80 the vehicle to considerable vertical strain, so that any reduction in weight, without sacrificing the stiffness against impact or without sacrificing resiliency to absorb impact, relieves the other parts of the vehicle as 85 well as the means of attachment, in direct proportion to the saving in weight of the impact bar.

While various modifications may be made in the practice of my invention as to the 90 methods of attaching the spring impact bar to the front or to the rear of a car, and the profile of the impact surface may be varied as shown and described in the original application of which this is a division,—this divisional application relates particularly to such bumper bars having the bands or stripes in a form preferably as shown in the drawings, their faces slightly inclined rearwardly or to the middle, that is in planes 95 converging from the top and bottom edges of the bumper away from a common plane and toward the slightly depressed intervening impact surface. While variations may be made, a particular embodiment is shown 100 in the accompanying drawings, in which:

Fig. 1 shows parts of two motor cars in collision, with the spring bar bumpers in

engagement to resist and absorb the impact.

Fig. 2 is a sectional view, on a larger scale of the spring bar members as they would engage in collision, indicating in dotted lines an alternate position of initial contact.

The spring bars 1 and 1^a constitute the main or impact portion of two bumpers with the impact faces 2 and 2^a in collision. In Fig. 2 the border surfaces or bands 3, 10 on spring bar 1, are slightly inclined from the upper and lower edge of the bar toward the middle depressed impact surface 4. Similarly spring bar 1^a has surfaces 3^a—3^a, 15 slightly inclined toward its depressed middle surface 4^a, so that in the event of disalignment or non-registering of colliding bumpers even a slight engagement at the edges will in all cases tend by the pressure of impact, as well as the slight vibration, to 20 cause the bumpers to slide into proper contact, that is nest together, or, in other words, to assume relative position that will assure transmission of the impact of engagement to be properly received and transmitted by the bumper and carried through 25 its resilient parts, so as to thus absorb the shock to the full extent of the resiliency and cushioning effect predetermined by the design of the bumper, thus greatly assuring 30 the proper functioning for which spring bar bumpers are intended.

In the dotted lines another position of a bumper 1^b is shown with its impact face depressed at 4^b, and with the slightly inclined marginal bands 3^b—3^b, showing one 35 of these bands only slightly over-lapping the lower band 3^a of spring bar 1^a, thus illustrating an initial contact which will cause the spring bar 1^a and 1^b to ride into 40 positive engagement, and thereby assure their proper functioning on collision.

While Fig. 2 shows the marginal bands protruding slightly beyond an intermediate impact surface, it will be understood that 45 the essentials are to provide suitable inclination of surface, which may be flat or slightly rounded, to assure colliding bumpers moving into a firm engagement for transmission of the collision shock in a substantially horizontal direction, and that instead of only two marginal bands, there may be 50 a different arrangement of impact bands to assure the same result. Essentially the specific form, and others that may equally 55 serve the purpose, assure a contact of sufficient surface to produce the results, but without ridges that would mar and indent impact surfaces of a bumper on collision. The construction thus provides for a 60 bumper impact profile that assures the proper functioning without a constant scarring, indenting, scratching or otherwise indelibly marring the bumper aspect. This aims for accomplishing the results stated 65 and still providing a very durable and in

every way serviceable spring bar bumper. The production of such bumpers also involves only regular formation by rolling of strip steel of uniform thickness bars, or at the most the formation of a bar having the 70 necessary spring tempering, with a slight deformation of the angle of band surface as shown. As illustrated in Fig. 2, the marginal bands on the impact surface are slightly above the intermediate depressed 75 impact area, and the inclination of the bands brings their merging into the depressed surface close, so that a slight groove, which may in cases be imperceptible, still provides for the proper and economical 80 polishing and nickelizing of the bands, and also their proper functioning.

Having the limited band or striped surfaces in a separate plane, the grinding which is an initial operation to prepare the 85 surface for nickel-plating, means that only a small fraction of area requires grinding compared with what was heretofore required for perfectly plain front bars. In addition, the intervening depressed surface 90 between the bands constituting a major portion of the front of the spring bar, lends itself most advantageously to any anti-rusting treatment or to finishing as by enamel in any colors. The grinding and finishing 95 of the bands also assures a uniform demarcation between the finish on the bands and the intermediate surface, thereby permitting facility and cheapness of finish with 100 uniformity in the completed article.

By the formation of the offset bands, to the limit of extent shown and described, the resiliency of the spring bar is not impaired, but stiffness and resistance to indentation or twisting and bending are increased, while 105 at the same time this relatively greater stiffness results with all the desired flexibility, as compared with a heavier bar having a plain front. The relatively protruding bands constitute a protection for the finish 110 such as enameling applied to the intermediate surfaces, so that in their use substantial advantage in durability of appearance and otherwise, is a practical result in addition to the relative lightness and greater resiliency, as well as strengthening, weight-for-weight as compared with a plain surface bar.

In operation, when used on an automobile, 115 the impact of this improved bumper involves an engagement with any part of another vehicle with the advantage of holding its contact upon impact instead of a tendency to slip up or down, which latter occurs with a plain surface. When such bumper engages the rear bumper of another car of similar profile, or having longitudinally banded contact surface, the engaging bands register with the respective depressed surfaces of the other bumper, thus preventing 120 125 130

any tendency to force one of the bumpers up, and consequently minimizing the vertical strain transmitted to the brackets or clamps which secure the bumpers to the relatively rigid parts of the vehicle. This characteristic insures the transmission of the impact more uniformly in a direct line and horizontally to the mass of the vehicle through the rigid parts of the structure best adapted to meet the shock of collision. Also preventing the slipping contact of engaging bumpers, minimizes the chance of a front bumper underrunning the rear bumper of a car, or overriding, so that one bumper would strike parts of the vehicle such as gasoline tank or headlights, liable to be seriously damaged. In the case of more than two slightly fore-set bands, their engagement with the impact face of the bumper on another car having similar profile, insures a gripping that minimizes the chance of relative vertical movement as compared with other forms of my bumper in which only two offset bands are used. The section of the bars as herein described, while conforming to what may be generally referred to as a channel section profile, involves in reality only a very slight depression, that is, a surface-profiling in the direction of the length of the bar. The offsetting of the edges, or the longitudinal portions forming the protruding strips or bands of the impact face, is not such as to constitute a rigid flange that would prevent resiliency. In the preferred form they provide borders or bands of sufficient width for stiffness and for the purpose of accommodating the grinding and polishing without having the tools therefor interfere with the intermediate surface. Thus as to various objects, simplicity of manufacture results with strengthening of the bar but without impairing the elasticity for the purpose of absorbing the shock and carrying and distributing the strain of impact to the desired substantial parts of the vehicle, without injury. Likewise, protection of radiator and lamps in the front, the tank in the rear, and any highly finished parts of the car proper is assured in addition to relieving all parts of the vehicle of shock.

Spring impact bars heretofore used have been made of plain smooth-face, spring bar stock which is tempered, and to suitably finish the same the entire front side or profile involves grinding of a surface the entire width of the front of the bar and also it will be understood that the production of spring bars involves tempering, and scale due to heat treatment more or less interferes with grinding necessary to condition the surface for plating. In all of this my construction involves a greatly diminished surface requiring grinding, and in practice represents in the neighborhood of a saving

of three quarters of the work in finishing the bars as compared with the finishing and nickel-plating of the entire front surface. The intermediate surfaces between the bands may be japanned in any color to match the finish of the other parts of the car, and in any event lends itself to a dull and relatively cheap treatment of the surface for its protection. The intermediate surfaces are, furthermore, partially protected by the slightly protruding bands.

By providing a cross-section of bumper bar as herein described, the structural advantages are attained, such as stiffening without interfering with flexibility, also strengthening and stiffening the top and bottom edges without increasing the weight compared with bars having a straight front impact surface,—attaining these advantages in equal strength with a diminution in weight as compared with a plain bar.

In order that bumpers on motor cars should effectively absorb the shock of impact, the bumper on a rear of a car must be engaged by the front bumper on a following car colliding with it. Uniformity of height of bumpers is therefore prescribed and is being more and more generally complied with by making the brackets carry the bumpers at the uniform height. However, original design and equipment are in practice subject to universal variation of load which depresses the vehicle springs, and is also subject to variation of tire inflation, which in road use precludes exact registration of bumper engagement. This with the slight vibration and road inequalities will always present a condition of variation of an inch or two between the heights of the rear bumper and the front bumper of a following car. Much of the failure of proper functioning of bumpers is caused by sliding of the smooth surface of bumpers, whereby one overrides the other and temporarily therefore they fail to properly absorb the impact on the spring bar bumper, which also frequently causes the permanent vertical dislocation of the impact bar at its attaching devices connecting it with the rigid parts of the vehicle.

The essentials involved in the features of construction of this application, serve to assure the proper functioning of colliding spring bar bumpers, as well as to maintain any one bumper in fixed relation to any other object with which it may collide, with the various advantages heretofore described. The construction in every respect also adds to the economy of production and economy of maintenance in service, at the same time realizing the superior functioning of bumpers for the purposes aforesaid.

While various modifications may be made from what is herein shown and specifically described without departing from my inven-

tion,—what I claim and desire to secure by Letters Patent is:

1. A spring impact bar for automobile bumpers having about three-quarters or less of its impact surface slightly depressed, and a plurality of longitudinal narrow smooth faced bands of impact surface projecting beyond the main surface, one of said projecting bands having the surface in a plane 10 slightly inclined toward the depressed surface area.
2. An automobile spring bar bumper having an impact face comprising top and bottom marginal flat faced bands of an aggregate width a quarter or more of the total width of the impact face, an intermediate impact surface slightly back-set from the surfaces of the bands, the flat surfaces of said bands being respectively in converging planes slightly inclined toward the back set intermediate impact surface.
3. A spring impact bar for automobile bumpers including a resilient bar having a plurality of slightly offset bands with flat impact surfaces together of greater width than the thickness of the bar, each surface being in a plane slightly inclined toward the middle of the impact face and with adjacent slight depressions of impact surface

adapted to engage similar offset bands of a 30 colliding impact bar, whereby over-riding of two such engaging bars of like impact face is prevented.

4. An automobile spring bar bumper having an impact face comprising a plurality 35 of longitudinal smooth faced bands of impact surface, and adjacent unfinished areas of impact face, a predominating surface of each band being inclined inwardly toward the middle of the bar, whereby interengaging bumper bars will tend to maintain their engagement for the purpose of transmitting horizontal shock absorption.

5. An automobile spring bumper having a broad thin impact bar, a band or strip 45 on the impact face of the bar extending longitudinally of the bar and of a breadth less than a quarter of the impact face of the bar and having the face of said band extending downwardly from the top edge 50 slightly inclined toward the body of the bar, and having a substantially symmetrical band along the bottom edge of the bar.

In testimony whereof, I have signed my name to this application this 12 day of 55 August, 1926.

SAMUEL H. SHAW.
